Primary Examiner — David Muller*Assistant Examiner* — Nathan Johnston(74) *Attorney, Agent, or Firm* — Muetting, Raasch & Gebhardt, P.A.**(57) CLAIM**

The ornamental design for an ovate filter cartridge end cap, as shown and described.

DESCRIPTION

FIG. 1 is a front perspective view of an ovate filter cartridge end cap of the claimed design;

FIG. 2 is front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

1 Claim, 5 Drawing Sheets---
